(57) **CLAIM**

The ornamental design for a colander, as shown and described.

DESCRIPTION

FIG. 1 is a top perspective view of a colander embodying the design of the present invention;

FIG. 2 is a top plan view of the colander shown in FIG. 1;

FIG. 3 is a side elevational view of the colander shown in FIG. 1, the colander being symmetrical about a vertical axis and the design is the same in all views around the axis; and,

FIG. 4 is a bottom plan view.

The design is characterized by the alternate rows of paired oblong or oval leaf-like holes and circular holes.

The broken lines are for illustrative purposes only and form no part of the claimed design.
